US0D1038112S

(12) **United States Design Patent** (10) Patent No.: **US D1,038,112 S**
(45) Date of Patent: ** Aug. 6, 2024

(54) **NOTEBOOK COMPUTER**

(71) Applicant: **Acer Incorporated**, New Taipei (TW)

(72) Inventors: **Cheng-Han Lin**, New Taipei (TW);
Kai-Teng Cheng, New Taipei (TW);
Pao-Ching Huang, New Taipei (TW);
Jui-Chieh Hsiang, New Taipei (TW)

(73) Assignee: **Acer Incorporated**, New Taipei (TW)

(**) Term: **15 Years**

(21) Appl. No.: **29/850,530**

(22) Filed: **Aug. 22, 2022**

(30) **Foreign Application Priority Data**

Apr. 7, 2022 (TW) 111301629

(51) LOC (14) Cl. **14-02**

(52) U.S. Cl.

USPC **D14/315**; D14/327

(58) **Field of Classification Search**

USPC D14/315-327, 344-347, 353-355,
D14/439-441, 444-446; D3/900, 902

CPC G06F 1/1641; G06F 1/1681

See application file for complete search history.

(57) **CLAIM**

The ornamental design for a notebook computer, as shown and described.

DESCRIPTION

FIG. 1 is a perspective view of a notebook computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The gradient pattern is printed on the top surface of the upper panel of the notebook computer. The dashed broken lines illustrate portions of the notebook computer that form no part of the claimed design.

1 Claim, 5 Drawing Sheets
